UNITED STATES PATENT OFFICE.

WALTER P. MURPHY, OF CHICAGO, ILLINOIS.

METAL END STRUCTURE FOR RAILWAY-CARS.

1,117,223.

Specification of Letters Patent. Patented Nov. 17, 1914.

Application filed February 24, 1913. Serial No. 750,222.

To all whom it may concern:

Be it known that I, WALTER P. MURPHY, a citizen of the United States, residing at Chicago, in the county of Cook and State of Illinois, have invented certain new and useful Improvements in Metal End Structures for Railway-Cars, of which the following is a specification.

My invention relates to the construction of railway cars and particularly to metal end structures for railway cars comprising metal sheets formed with hollow ribs or corrugations. If a sheet metal end corrugated or ribbed in this way is subjected to a local thrust of very considerable momentum, that is, a thrust applied to one of the corrugations, as is likely to be the case when the car is loaded with a heavy movable or shifting cargo, it is possible, as experience with these structures has demonstrated, that the impact will stretch or press out such corrugation and those adjacent thereto, and so deform the end and decrease its strength and capacity for resistance. This tendency may be overcome, to a certain extent, by making the end sheets of very thick metal but this is objectionable because it adds to the cost of the structure and also to its weight.

One of the principal objects of my present invention is to provide efficient means for preventing the ribs or corrugations from being stretched or pressed out by local thrusts of abnormal momentum which will add but little to the weight of the end structure and will not materially increase the cost of manufacture. The expedient which I have devised for this purpose consists in providing on the face of the end sheet, or end sheets, one or more tie members which are attached to the end sheets at convenient intervals, preferably on each side of each corrugation so that they provide, in effect, tension members extending across the hollows formed by the corrugations. Preferably these tie members extend across the corrugations from edge to edge transversely of the corrugations and are formed with longitudinally pressed out ribs so that they serve not only to tie the corrugations against the tendency to flatten out under local impacts but also reinforce and strengthen the entire end structure as against the thrusts of the cargo as a whole and as against the twisting stresses to which the end structure of a car is subjected because of the tendency of the car to "weave."

The invention has for further objects to provide certain other improved constructions, arrangements and devices relating to sheet metal car ends which will be herein-after described and claimed.

The invention is illustrated, in a preferred embodiment, in the accompanying drawings wherein—

Figure 1 is an end elevation of a railway car fitted with the sheet metal end structure of my invention; Fig. 2, a sectional view, taken on line 2—2 of Fig. 1; Fig. 3, a side elevation of one end of the car; Fig. 4, a sectional plan on line 4—4 of Fig. 1; Fig. 5, a view, in perspective, of one of the reinforcing or tie members shown in the preceding figures; Fig. 6, a view, in elevation and upon an enlarged scale, of the door shown in Figs. 1 and 2; Figs. 7, 8 and 9, sectional views taken on lines 7—7, 8—8 and 9—9, respectively, of Fig. 6 looking, in each case, in the direction of the arrows; Fig. 10, a fragmentary end elevation of a modified end structure; Fig. 11, a side elevation of this construction; Fig. 12, a view, in perspective, of the reinforcing or tie member shown in the preceding two figures; Fig. 13, a fragmentary sectional view taken on line 13—13 of Fig. 10, and Figs. 14 and 15, perspective views of the devices employed for attaching the reinforcing member to the framing of the car.

Like characters of reference designate like parts in the several figures of the drawings.

Referring to the drawings, 25 designates the corner posts of a railway box car of ordinary construction, 26 an end plate, 27 the side plates, 28 the roof, 29 an end sill, 30 the flooring, and 31 the belt rails.

The end structure consists of three end sheets 32, 33 and 34, and a pair of reinforcing or tie members 35; although it will be understood that the number of the sheets and of the tie members might be varied within the discretion of the constructor. The end sheets are formed with a series of, in the case shown, inturned corrugations or hollow ribs 36 and on their vertical edges with flanges 37 which overlap the sides of the car. The lower plate 34 has preferably the inturned flange 38 which is riveted to the end sill 29. Waterproof joints are made between the several end sheets in any suitable manner, for example, by simplylapping the lower edges of the upper sheets.

over the upper edges of those below, as shown in the drawings.

The reinforcing or tie members 35 are arranged preferably, though not necessarily, 5 on the outside of the end and are attached to the end sheet, preferably by means of rivets 39, on each side of each of the inwardly extending corrugations. By this expedient tension members are provided for the several corrugations which check the tendency 10 of the corrugations to be flattened out under impacts to which they may be subjected. I have referred to the inward bends of the sheets as ribs or corrugations but it will be 15 clear that the term is used arbitrarily in this regard as the outward bends might be so described without doing violence to the term.

Preferably the reinforcing members 35 extend from top to bottom of the end structure and are formed with outwardly pressed 20 ribs 40. These ribs are, by preference, widest and deepest at a point below the central horizontal line of the car end and are tapered toward their extremities as shown. The 25 purpose of this is to give the greatest amount of reinforcement to the end in its lower portion which, as railway cars are ordinarily loaded, has to withstand the most violent thrusts, when the car, for example, is loaded 30 with car wheels, rails, piping, or other heavy articles likely to shift by inertia when the train stops and starts. The upper sheet 35 is preferably secured to the end plate 26 by bolts 41 and is overlapped by a fascia plate 35 42. The flanges 37 are secured to the corner posts 25 by means of the bolts 43. I also 45 preferably provide certain anchoring devices which secure the end structure to the belt rails 31, for example, at each side of the car and at the level of each belt rail (if the car, 50 as in the case shown, has more than one belt rail). Angular members 44 are secured to the flanges 37 of the end sheet and to the belt rails 31 through the side sheathing 45 55 of the car. These members have flanges 46 which overlap the end of the car holding the edges of the end sheets pressed against the corner posts. I also preferably provide, 60 within the car, the anchoring straps 47 which are secured to the belt rails and have bolt-like extremities 48 which pass through perforations in the end sheets and are secured thereto by nuts 49 bearing against the washers 50.

55 In addition to the devices just described the end structure may be provided with gusset plates 51 for attaching the edges of the upper sheet to the side plates 27 of the car and with the angularly disposed members 52 for attaching the lower corners of the lower end sheet to the side sills 53. Certain of these anchoring devices may be dispensed with if a maximum security of attachment is not required.

65 A car end constructed and secured to the

car as above described is capable of withstanding, without being deformed, broken or detached, the severest impacts, pressures and other stresses both of local and general character, to which the end of a freight car is subjected when in service, even though the end sheets, as is very desirable for reasons of economy and to minimize cost, be made of relatively thin stock. The end structure will also successfully resist the tendency to warp and distort due to the weaving stresses to which a freight car is subjected.

In Figs. 1 and 2 of the drawings I have shown the upper sheet 32 pierced by a circular door opening which is closed by a sheet metal door 54. The details of the door construction are best shown in Figs. 6 to 9 inclusive, the primary purpose of the particular construction shown being to minimize the weakening effect which would ordinarily result from piercing a relatively thin sheet of metal with an opening of the size required. In order to provide for a door in the end which will not materially weaken it, a circumferential frame member 55 is provided having a flange 56 which is pressed to conform to the corrugations 36 of the end sheet, the flange 56 being secured to the inner face of the sheet. This annular door frame therefore takes up the stresses exerted against the interrupted corrugations and transmits them around the door opening. This effect is carried out further in the construction of the door itself and the means used for fastening it in closed position. The door consists of a circular dished sheet of metal formed preferably with the inturned flange 57. The door bears against an outwardly turned rim 58 formed on the annular member 55. The door is dished or convex and, being of sheet metal, is, to a certain extent, elastic. It is pressed against the door frame, making a close fit therewith, by means of a bar 59 pivoted to a casting 60 at one side of the door and formed at the other end with a slot 61 through which the threaded end 62 of an I-bolt may extend. The I-bolt is pivoted by means of a pin 64 to a casting 65 secured to the end sheet. The door is preferably secured to the bar 59 by a rivet 66 which is upset on the inside against a washer 67 and on the outside against a washer 68 bearing against the end of a spacing sleeve 69. The bar 59 is pressed against the door and the door against its frame by means of a nut 70 on the bolt 63. This nut is preferably formed with one or more lugs 71 perforated for the seal pin 72. When the door is screwed down against the annular member 55 the bar 59 and the door form a truss across the door opening which transmits the stresses on the interrupted corrugations. The door is somewhat loose on the bar 59, as shown, and this circumstance, together with its elasticity, insures a proper

seating on the door frame 55. As end doors are ordinarily used for loading lumber, the door in question is preferably provided with a roller 84 which has journals 85 mounted in bearing castings 86 secured to the inside of the door frame member 55, the roller being kept in place by cotter pins 87.

In the modified construction shown in Figs. 10 to 15 inclusive, the end sheets are 10 designated 73, 74, 75, the upper sheet 75 being formed at its upper edge with the in-turned flange 76 on which the ridge pole 77 and purlins 78 are supported, the flange taking the place of the usual end plate. A reinforcing or tie member 79 is employed 15 which is formed with the rib 80 increasing in width and depth from the top to the bottom of the strip. This strip or post is secured to the channel iron ridge pole 77 by the angular casting 81 (Fig. 14). It may be 20 secured to the end sill 82 by means of the casting 83 (Fig. 15). The vertical edges of the end sheets are shown as secured to the framing of the car in substantially the same 25 manner as in the construction hereinabove described, except that the end flanges 46^a of the angular tie members 44^a are large enough so that they take the ends of the anchoring straps 47^a, these latter being the 30 same in construction and in their attachment to the frame of the car as the devices 47 hereinabove described.

While I have described my invention in a preferred embodiment, it will be understood 35 that I do not wish to be limited to the precise constructions, arrangements and devices disclosed.

I claim:

1. The combination with end frame members and belt rails of a railway car, of a 40 metal end structure comprising an end sheet having flanges overlapping the sides of the car, anchoring members for said end sheet on the inside of the car secured to said belt 45 rails and extending through and secured to said end sheet.

2. The combination with the end frame

members and belt rails of a railway car, of a metal end structure comprising an end sheet having flanges overlapping the sides 50 of the car, anchoring members for said end sheet on the inside of the car secured to said belt rails and extending through and secured to said end sheet, and angular members on the outside of the car secured to the belt rails 55 and having flanges which bind the sheet against the end frame of the car.

3. The combination with the end frame members and belt rails of a railway car, of a metal end structure comprising an end sheet 60 having flanges overlapping the sides of the car, angular members on the outside of the car secured to said belt rail and having flanges which bind the sheet against the end frame of the car, and anchoring members 65 on the inside of the car secured to said belt rails and extending through said end sheet and through the end flanges of said angular members.

4. The combination with the ridge pole 70 of a railway car, of an end structure comprising a corrugated metal end sheet, and a vertically extending reinforcing member secured at intervals to said end sheet and attached to said ridge pole. 75

5. The combination with the upper and lower end frame members of a railway car, of a sheet metal corrugated end structure and a vertically extending reinforcing member secured at intervals to said end sheet 80 and attached to said upper and lower end frame members.

6. The combination with the upper and lower end frame members of a railway car, of a sheet metal end structure formed with 85 horizontal corrugations, and a vertically extending reinforcing member secured at intervals to said end sheet and attached to said upper and lower end frame members.

WALTER P. MURPHY.
